UNITED STATES PATENT OFFICE.

FRANK CAVALLARO, OF SAN JOSE, CALIFORNIA.

FIRE HYDRANT.

Application filed July 6, 1921. Serial No. 482,648.

To all whom it may concern:

Be it known that I, FRANK CAVALLARO, a citizen of the United States, residing at city of San Jose, in the county of Santa Clara and State of California, have invented new and useful Improvements in Fire Hydrants, of which the following is a specification.

This invention relates to a fire hydrant.

It is the principal object of the present invention to provide a fire hydrant having a structure which will permit it to be readily used in forming a hydrant having a plurality of separately controlled outlet connections, said structure embodying a valve which is not liable to freeze and which may be readily operated without vibrating.

The present invention contemplates the use of a hydrant having a lower compartment in direct communication with the water main and an upper compartment in communication with outlet connections. Said compartments being separated by a valve wall, having an opening therethrough and which opening is adapted to be closed by a valve member disposed in the upper compartment and acting against pressure of the water in the lower compartment.

The invention is illustrated by way of example in the accompanying drawing in which:

Figure 1 is a view in section and elevation showing a hydrant with which the present invention is concerned.

Fig. 2 is a view in plan showing the hydrant with parts broken away for the sake of clearness.

Referring more particularly to the drawings, 10 indicates a hydrant casing, the lower portion of which forms an inlet compartment 11 secured by a bolting flange 12 to a water main of suitable capacity. In the present case the hydrant is formed with two outlets and it will be understood that one or more outlets may be used without departing from the spirit of the present invention, in which case the inlet compartment 11 will supply all of the water required from the main. When two outlets are provided the upper wall 13 of the inlet compartment 11 is preferably formed with a deflecting rib 14 which would tend to direct the flowing water toward valve openings 15. These openings extend through the horizontal partition wall 13 and establish communication between the lower compartment 11 and upper compartments

16 and 17. The outlet compartment 16 is in communication with an outlet opening 18, which opening is surrounded by suitable tubular connection for receiving the end of a fire hose not shown in the drawing. An outlet member 19 of larger capacity than that shown at 18 is shown as being formed through the wall of the compartment 17. The provision of outlet openings of different diameters permits hose lines of different sizes to be employed. The compartments 16 and 17 are separated by a vertical partition wall 20. The tops of the two separate compartments are closed by caps 21 held in position by bolts 22. The caps are formed with central bosses 23 which receive internally threaded sleeves 24. The sleeves are formed with an enlarged collar at their upper ends and are externally threaded at their lower ends to receive lock nuts 25. A threaded valve stem 26 extends through each of the sleeves 24 and, of course, engages the threads thereof. The upper end of this stem is formed with flat faces to receive a wrench by which the stem may be rotated. Mounted upon the lower end of each of the valve stems is a frusto-conical valve member 27 which is adapted to be forced down upon a tapered valve seat 28. This valve seat circumscribes the opening 15 through the wall 13 and may be interchanged. The valve member 21 may be formed of any desired material and is here shown as comprising an enlarged collar 29 carried at the lower end of the stem 26 and against which the valve member is secured. A washer 30 and a nut 31 hold the valve member in position against the collar 29 and permit the removal and repair of the valve. Attention is directed to the fact that the tapered face of the valve seat diverges toward the upper end thereof, thus making it necessary to force the valve member down against the seat and against the upward pressure of the water in the main.

In operation of the present invention the hydrant is constructed and assembled as shown in the drawings. The valves 21 may normally be held upon their seats 28 and will resist the upward pressure of the water in the compartment 11. When it is desired to open one of the valves its stem 26 is rotated to lift the valve away from its seat and in a counter direction to the pressure of the water. This will allow the upper compartment 16 or 17 to be filled with water

and the water to pass out through the outlet members 18 or 19. In hydrants of present construction it often occurs that the valve stems break and due to the fact that the valve is on the pressure side of the valve seat it is quite difficult to make a repair. With applicant's invention the breaking of a valve stem would not involve any great inconvenience as the stem would normally 10 press down to hold the valve in position and when retracted would permit the valve to be readily withdrawn. In hydrants commonly used an objectionable vibration of the pipes in adjacent buildings often takes 15 place due to the fact that the valve members are operating against the pressure of the stream when they are opened. This is eliminated by causing the valves to operate with the stream. In cold climates it is necessary 20 to provide some means for draining the hydrants to prevent them from freezing, while in the present case it will be seen that the compartment above the valve seat may be drained due to the position of the outlet 25 openings near the floor 13, in other words when the valves are closed water in the compartments 16 and 17 may be drained thru the outlet openings. This will insure that the valves will not be maintained under water and that they may be readily opened by 30 rotation of the stems assisted by the pressure of the water in the main.

It will thus be seen that the device here disclosed while simple in construction and 35 readily permitting the use of hose lines of any required diameter will at the same time prevent vibration and freezing of the valve while permitting the hydrant to be readily repaired.

While I have shown the preferred form 40 of my invention as now known to me, it will be understood that various changes might be made in the combination, construction and arrangement of parts by those skilled in the art without departing from the spirit 45 of the invention as claimed.

Having thus described my invention, what I claim and desire to secure by Letters Patent is:

A fire hydrant comprising a cylindrical 50 lower inlet compartment having a flange whereby it may be connected to a water main, a pair of upper outlet compartments formed above the inlet compartment and disposed on opposite sides of the center 55 thereof, a horizontal partition wall separating the outlet compartment from the inlet compartment, said outlet compartments each having a discharge opening whereby they may be connected to a hose, said discharge opening being located in close proximity to said partition wall whereby the outlet compartments may be substantially 60 drained, said horizontal partition wall having tapered valve openings formed therein 65 between each outlet compartment and the inlet compartment, tapered valve members adapted to seat in and close said openings, a separate covering cap for the upper end 70 of each outlet compartment, each cap having a threaded bore, a threaded valve stem for each valve member, said stem extending through said threaded bore in the cap and threadedly engaging the same, the upper 75 ends of said stems projecting from said caps whereby they may be turned to raise the valves from their seats.

FRANK CAVALLARO.
